UNITED STATES PATENT OFFICE.

JULIA A. KING, OF CHICAGO, ILLINOIS.

LEGGIN.

SPECIFICATION forming part of Letters Patent No. 293,475, dated February 12, 1884.

Application filed November 26, 1883. (No model.)

To all whom it may concern:

Be it known that I, JULIA A. KING, of Chicago, in the county of Cook and State of Illinois, have invented certain new and useful 5 Improvements in Leggins Worn over the Shoes or other Clothing for the Feet; and I do hereby declare that the following is a full, clear, and exact description thereof, reference being had to the accompanying drawings, and to the 10 letters of reference marked thereon, which form a part of this specification.

The improvements herein described relate to that class of leggins worn usually by ladies, which are composed of a knitted elastic fabric 15 and commonly extend to or above the knee. Said improvements have for their objects, first, to better confine the lower edge or bottom of the leggin about the foot, in order that said leggin may be drawn more tightly upward 20 about the ankle and limb; second, to insure a neater appearance of the leggin upon the foot; and, third, to permit an overshoe to be worn, if desired, without the inconvenience of tucking the lower edges of the leggin beneath the 25 same, and the discomfort arising from thus confining the leggin, or without the unsightly appearance that is produced when said leggin escapes from confinement beneath the overshoe.

Heretofore elastic leggins of the class described have been made of such length and form at their lower end as to overlie the instep only, and have been held down by a simple strap passing from one edge to the other 35 of the leggin beneath the hollow of the foot. In this former construction the lower edge or end of the leggin, unless confined by an overshoe, is loose over the instep and about the heel, and both presents an unsightly appearance, and readily admits snow beneath it. The leggin is also incapable of being drawn snug and smooth about the ankle and upper part of the foot, and it must be tucked beneath the overshoe when the latter is worn, from which 40 it is liable to escape, or forms an uncomfortable ridge within the same, if held thereby. In the construction herein set forth the leggin is extended over the foot and is confined in place by a light or thin sole, which preferably extends back to the heel, and to which the 45 knitted fabric is joined after the manner of

joining the uppers of shoes to their soles, either directly or by lengthening it out by a tip or foxing, as the case may be. The opening left at the bottom for the heel of the shoe 55 to pass through is bordered by a strip of leather or similar material, so as to hug the heel or the shoe in the neighborhood of the heel closely, and to thereby prevent the admission of snow at this point, and also to retain 60 the rear portion of the foot of the leggin in place while the latter is drawn upward about the limb. The heel-piece referred to also has the advantage of giving a neat appearance to the device when on the foot, and of preventing 65 wear and stretching of the knit fabric at this point.

In the accompanying drawings, Figure 1 represents a knitted leggin containing my improvement. Fig. 2 represents the lower portion of the leggin shown in Fig. 1 applied over a lady's garter or boot.

A is a knitted leggin of the usual description, but having its lower end prolonged to project over the foot to the lower margins 75 thereof at the sides and at the toe, where it is joined with a thin flexible sole, B, of leather or other suitable material. The prolongation of the knitted leggin necessary to reach the sole may be produced either by the addition 80 of the necessary stitches to give the desired extension of the fabric, or by the addition of a toe-piece, a, which may be extended rearwardly along the sides of the foot to any desired extent to form what is technically known 85 as a "foxing." As illustrated in the drawings, an opening is left at B' to admit the heel H of the shoe, and in this case the sole B will preferably terminate at or near the heel, as plainly indicated in Fig. 2. The free margin of the 90 leggin about the heel is bound or bordered by a leather or other heel-piece, a', cut of proper shape or otherwise adapted to cause the same to fit closely about the quarter or counter of the shoe, and to thereby prevent the admission 95 of snow or other matters beneath the leggin, and to give a desirably neat appearance to the device at this point. Said heel-piece a' will also obviously have the effect of giving durability to the structure at the point where 100 it is applied, and will also hold the rear portion of the leggin-foot down about the shoe,

and thereby permit the leggin to be drawn upwardly over the limb sufficiently to cause the same to lie smooth over the foot and ankle.

It will be observed that the heel-piece a' is extended forwardly far enough to unite with the sole B , by which means the lower edge of the fabric is protected at all points, so as to prevent its tearing, and whereby said heel-piece a' will always serve to confine the leggin closely about the counter of the shoe.

I claim as my invention—

1. As an improved article of manufacture, an elastic knitted leggin extended to cover the upper surface of the foot, and provided with a

partial sole, B , and heel-opening at B' , substantially as described.

2. The combination, with the elastic knitted leggin extended to cover the upper surface of the foot, of a partial sole, B , and a facing or binding, a' , about the heel-opening B' , substantially as and for the purpose set forth.

In testimony that I claim the foregoing as my invention I affix my signature in presence of two witnesses.

JULIA A. KING.
